[57] CLAIM

The ornamental design for a portable computer, as shown and described.

DESCRIPTION

FIG. 1 is a reduced perspective front view of the portable computer comprising the present invention;

FIG. 2 is a reduced perspective rear view of the portable computer comprising the present invention;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a left side view of an alternative embodiment of the portable computer comprising the present invention showing an aperture for an A/C plug in the side panel of the base and the undisclosed views are identical in appearance to those of the first embodiment; and, FIG. 10 is a reduced additional front perspective of the portable computer showing the display panel in a tilted position.
